(57) **CLAIM**

The ornamental design for a microwave mug cooker device,
as shown and described.

DESCRIPTION

A portion of the disclosure of this patent document contains
material which is subject to copyright protection. The copy-
right owner has no objection to the facsimile reproduction
by any one of the patent document or the patent disclosure,
as it appears in the Patent and Trademark Office patent file
or records, but otherwise reserves all copyright rights what-
soever.

FIG. 1 is a perspective view of a mug cooker showing our
new design;

FIG. 2 is a perspective view of a mug cooker in a two-
member open configuration;

FIG. 3 is a perspective view of a bottom member of the mug
cooker;

FIG. 4 is a perspective view of a top member of the mug
cooker;

FIG. 5 is a front perspective view of a mug cooker;

FIG. 6 is a top view of a mug cooker

FIG. 7 is a right side view of the mug cooker;

FIG. 8 is a left side view of the mug cooker;

FIG. 9 is a rear view of the mug cooker; and,

FIG. 10 is a bottom view of the mug cooker.

1 Claim, 10 Drawing Sheets
